UNITED STATES PATENT OFFICE

152,009

DESIGN FOR A PROTECTOR FOR BABY'S SHOE

Verne L. Lyons, Minneapolis, Minn.

Application May 20, 1947, Serial No. 139,147

Term of patent 7 years

(Cl. D7—4)

To all whom it may concern:

Be it known that Verne L. Lyons, a citizen of the United States and resident thereof and of Minneapolis, in the county of Hennepin and State of Minnesota, has invented a new, original, and ornamental Design for a Protector for Baby's Shoe, of which the following is a specification, reference being had to the accompanying drawing, forming a part thereof.

Figure 1 is a perspective view of the protector for baby's shoe, showing my new design;

Fig. 2 is a top plan view of the same; and

Fig. 3 is a side elevation of the same.

The dominant features of my design for the protector for baby's shoe shown, reside in the specific configuration of the rear edge portions, in combination with the strap-supporting ears at opposite sides thereof.

I claim:

The ornamental design for a protector for baby's shoe, as shown and described.

VERNE L. LYONS.
